US00D632570S

(12) **United States Design Patent**
Caldwell et al.

(10) **Patent No.:** **US D632,570 S**
(45) **Date of Patent:** **** Feb. 15, 2011**

(54) **CONDIMENT PACKAGE CONTAINER**

(75) Inventors: **Craig Caldwell**, Slippery Rock, PA (US); **John Marshall**, Pittsburgh, PA (US); **William Rasile**, Allison Park, PA (US)

(73) Assignee: **H.J. Heinz Company**, Pittsburgh, PA (US)

(**) Term: **14 Years**

(21) Appl. No.: **29/364,634**

(22) Filed: **Jun. 25, 2010**

(51) **LOC (9) Cl.** **09-07**

(52) **U.S. Cl.** **D9/435**

(58) **Field of Classification Search** D9/710, D9/701, 702, 707, 499, 457, 456, 455, 454, D9/438, 435, 434, 432, 431; 229/123.1; 220/359.3, 359.1, 265, 259.2-259.4; 215/232; 206/530

See application file for complete search history.

(57) **CLAIM**

The ornamental design for a condiment package container, as shown and described.

DESCRIPTION

FIG. 1 is a perspective view of the condiment package container;

FIG. 2 is a front view of the condiment package container;

FIG. 3 is a side view of the condiment package container;

FIG. 4 is a top end view of the condiment package container; and,

FIG. 5 is a bottom end view of the condiment package container.

The broken lines in the figures depict environment only, and form no part of the claimed design. Additionally, in FIG. 3, the broken lines depict the bounds of the claim and form no part of the claim.

1 Claim, 2 Drawing Sheets
